Isaac De Gouche, of St. Louis, Missouri,

Assignor to

Bridge, Beach & Co., of same place.

Letters Patent No 1280. Dated July 3, 1860.

The schedule referred to in these Letters Patent and making part of the same.

To all whom it may concern:

Be it known that I, Isaac De Gouche, of the City and County of St. Louis and State of Missouri, have invented or produced a new and original design of a Box Heating Stove, and I do hereby declare that the following is a full and exact description of the same, reference being had to the accompanying drawings, and to the letters of reference marked thereon, making a part of this Specification.

A. represents a perspective view of my stove, the ornamentation of which is shown in the detail drawings, B E.D.

B. represents one half of the side plate. B.C. - D. represents the end seen in the perspective view A. - E represents the other end. E, F, are the corners which consist of bands crossing each other, with rosettes at their intersections. G is the dividing member between the two halves of the side plate, B.C. and exactly resembles E, F. - H, H. is a scroll ornament, enclosing the Arms of Missouri, I, I.

Above the scroll ornament H, H. is the word "Missourian" I. is a scroll ornament on which is the word "Missourian". K. is a scroll ornament, L, L. is an ornamental shield, oval in form, bearing the word "Bridge, Beach & Co, St. Louis", with scroll work at the sides and bottom, and surmounted by a helmet with feather and flowing foliage.

In the centre of L, L. are rosettes forming diaper work. The Arms of Missouri, I, I. I do not claim as new, but only the arrangement of it in connection with the other ornaments as herein described.

Having thus described my Design of Box Heating Stove, what I claim as new therein and desire to secure by Letters Patent, is -

The ornamental configuration and Design of Box Heating Stoves herein described and shown in the annexed drawings.
